ATTORNEY

UNITED STATES PATENT OFFICE.

MATTI NIEMI, OF SEATTLE, WASHINGTON.

COMBINED MUSIC-LEAF HOLDER AND TURNER.

Application filed July 5, 1921. Serial No. 482,492.

To all whom it may concern:

Be it known that I, MATTI NIEMI, a citizen of Finland, residing at Seattle, in the county of King and State of Washington, have invented certain new and useful Improvements in Combined Music-Leaf Holders and Turners, of which the following is a specification.

This invention relates to music leaf holders and turners.

An object of my improvements is the provision of an inexpensively constructed and efficient device of this character which is adapted to be folded to occupy a small space. Another object of the invention is the provision of simple and durable means which are operable by a player's foot for conveniently turning music leaves.

Other objects and advantages of the invention will appear from the following description.

The invention consists in the novel construction, adaptation and combination of parts hereinafter described and claimed.

In the accompanying drawings,—

Figure 1 is a front elevational view of a music stand embodying my invention. Fig. 2 is a horizontal sectional view taken substantially through 2—2 of Fig. 1, with one of the leaf-turning levers illustrated in a different position from that in which it is represented in Fig. 1. Fig. 3 is a horizontal section through 3—3 of Fig. 1. Fig. 4 is a view in front elevation of portions of the operating connections for one of the leaf turners, a portion of the latter and the supporting bracket therefor being shown in longitudinal vertical section. Fig. 5 is a detail vertical section through 5—5 of Fig. 3. Fig. 6 is a fragmentary perspective view of Fig. 1.

In said drawings, the reference numerals 10 and 10¹ represent telescopically arranged tubular members of a post. Said post is supported by three foldable legs such as 12 including brace elements 13, which are connected by pivot pins 14 to ears of collars 15 provided upon the post member 10¹.

The post member 10 is formed with a chisel-like upper extremity 10² (Fig. 2) which engages in a socket provided in a bar 16 which serves as an extension of said post. Connected to the lower portion of the bar 16 by pivots 16¹ are complementary bracket members 17 and wing bars 18. Said bars, bracket members and connecting link ele-

ments 18¹ constitute a frame which is removably connected to the post and is capable of being folded into a small compass by swinging the bracket members and wing bars upwardly against the part 16.

The bracket members 17 are in the nature of angle-rails, each having a horizontal flange element 17¹ and a vertical flange element 17², the adjacent ends of the flanges 17¹ being formed to abut against each other for retaining the rail members in alignment with each other when in use.

Supported upon each of said bracket members is a horizontal lever 19 which is fulcrumed by a pin 9 to the respective bracket flange 17¹ at a distance from the post axis and with respect to the lever to afford relatively short and long arms 19¹ and 19² thereto.

Carried by the long arm of a lever are paper-sheet engaging devices in the nature of clips 20¹, 20², 20³ and 20⁴. The clip 20¹ is fixedly secured to a lever in proximity to the fulcrum thereof, the clip 20² extends laterally from the upper end of a substantially vertical rod 21 which is also fixedly secured to the lever in proximity to the lever fulcrum.

The clip 20³ is slidable longitudinally on the lever and the clip 20⁴ extends laterally from a rod 21¹ which is disposed in the plane of the rod 21 and is connected to the respective lever for movements longitudinally thereof. By thus arranging the clips a paper leaf or sheet indicated by A in Fig. 1, is engaged at its lower edge and at opposite sides near its top for different widths of leaves. The bracket flanges 17² are respectively provided with slots 22 to accommodate the shorter arms 19¹ of the levers when being swung in the turning of a sheet.

For effecting sheet turning movements of a lever, the short arm 19¹ thereof is connected, as shown in Fig. 4, by means of a link 23 with swivel attachments 24 of wires 25 and 25¹ which extend over guide pulleys 26 and 26¹ connected at opposite sides of the respective fulcrum pin 9 to said frame.

To the wire ends below said pulleys are secured hooks 27 which are engageable in selected links of chains 28 which are connected by wires 29 with the ends of pedal devices 30, one for each of the aforesaid levers.

Said pedal devices are in the nature of levers which are fulcrumed at their mid-

lengths to standards 31 extending upwardly from a floor plate 32 disposed transversely with respect to the music stand.

33 represents a vertical bar extending 5 from the floor surface into the post member 10¹ and having a forwardly directed foot element 33¹ which overlies and is connected to the central portion of the floor plate 32 by means of a pivot pin 34.

10 Mounted upon the foot element 33¹ is a sleeve 35 which is engageable over a rearwardly directed tongue 36 provided on the floor plate 32 whereby the latter is rigidly secured in rectangular relations to the foot 15 element 33¹.

Said floor plate is furthermore connected from its ends to hook plates 37 which are releasably engageable with the adjacent legs 12 by spring latches 38.

20 39 represent clips secured to the bracket members 17 for engaging sheets which are not necessary to turn.

In operation a sheet of music attached to either of the levers 19 by the respective clips 25 is turned about the fulcrum pin 9 therefor through the medium of the flexible connections and the associated pedal lever 30.

By depressing the more elevated arm of the 30 pedal lever a pull is exercised through such connection to the short arm 19¹ of lever 19

to cause the longer or sheet carrying arm 19² to be swung to one side of or medially of the post axis.

This arrangement of the levers and brackets will be understood from an inspection of Fig. 2 wherein lever 19 which is pivoted to the bracket at the left hand side of the stand is represented in crossed relations thereto, and the other lever 19 is entirely at one side of the post axis. 35 40

What I claim, is,—

In apparatus of the class described, a frame comprising a centrally disposed bar and two horizontally aligned bracket members pivotally connected thereto, a lever pivotally connected to each of said bracket members, said pivots being disposed with respect to the levers to afford a long and short arm to each of the latter, sheet engaging clips provided on the long arms of the respective 50 levers, pedal devices, and flexible connections between said devices and the short arms of said levers for turning the latter about their respective pivots. 45

Signed at Seattle, Washington, this 25th 55 day of June, 1921.

MATTI NIEMI.
